Primary Examiner — Michael C Stout*Assistant Examiner* — Fitzgerald L Butac(74) *Attorney, Agent, or Firm* — Ladas & Parry LLP(57) **CLAIM**

The ornamental design for the shaker screen, as shown.

DESCRIPTION

FIG. 1 is a top plan view of a shaker screen in accordance with the present invention;

FIG. 2 is a bottom plan view thereof;

FIG. 3 is a left side elevation view thereof;

FIG. 4 is a right side elevation view thereof;

FIG. 5 is a front elevation view thereof;

FIG. 6 is a back elevation view thereof;

FIG. 7 is a top perspective view thereof; and,

FIG. 8 is a bottom perspective view thereof.

The broken lines show portions of the shaker screen that form no part of the claimed design.

1 Claim, 8 Drawing Sheets(56)
